[57] **CLAIM**

The ornamental design for a bicycle frame assembly, as shown and described.

DESCRIPTION

FIG. 1 is a right side view of a bicycle frame assembly according to my novel design;

FIG. 2 is a left side view of the bicycle frame assembly according to my novel design;

FIG. 3 is a front view of the bicycle frame assembly according to my novel design;

FIG. 4 is a rear view of the bicycle frame assembly according to my novel design;

FIG. 5 is a top view of the bicycle frame assembly according to my novel design;

FIG. 6 is a bottom view of the bicycle frame assembly according to my novel design;

FIG. 7 is an enlarged fragmentary side view of the central portion of the bicycle frame assembly according to my novel design; and,

FIG. 8 is an enlarged fragmentary side perspective view of the central portion of the bicycle frame assembly according to my novel design.

Features shown in broken lines depict the environment and do not form part of the claimed design.
